AUTOMATIC LATHE

Ernest J. Svenson, Rockford, Ill.

Application December 21, 1931, Serial No. 582,192

38 Claims. (Cl. 82—2)

My invention relates generally to material working apparatus and particularly to hydraulically controlled machines, such as automatic lathes and the like.

5 In general it is one of the primary objects of my present invention to provide material working apparatus, such as lathes and the like, having improved structural characteristics equipped with an improved system of hydraulic control, 10 whereby the required amount of time, skill, and effort of a machine operator is materially reduced and the quality of work produced by the machine is of a very high standard.

15 In these days of line production there is a demand for machines which are capable of increased production without impairing the quality of the work produced, and to this end my invention contemplates the provision of a machine which is capable of performing heavy duty 20 cutting operations quickly and accurately.

There is also a present demand for material working apparatus or machines which are particularly adapted to effectively employ the relatively tough, hard cutting alloys which have been 25 developed in recent years, such as tungsten carbide, etc., and it is one of the objects of my present invention to provide a machine having certain structural characteristics which lend sufficient sturdiness or rigidity for rendering the 30 machine particularly adaptable to be equipped with such cutting tools. I have found, after operating machines constructed in accordance with my invention for several months in actual production work in the shop, that the surface 35 speed of cutting by using tungsten carbide tools has increased from three to four times over the speed previously obtained by the use of other conventional machines with which I am familiar. Consequently by employing my improved 40 machine construction a marked increase in production is experienced.

Another object of my present invention is not only to provide a machine of rigid and sturdy construction as above set forth, but one in which 45 the total mass or weight is considerably reduced, and in which many of the parts, which in conventional machines are bolted together, are, according to the present invention, formed integral. To this end I propose to provide a novel 50 machine bed comprising a single casting having a large portion thereof cored so as to reduce its weight, and to eliminate the usual bolting of machine frames, I propose to cast the machine bed, spindle supporting head, etc., in a single integral 55 unit, thereby providing an extremely rigid sup-

port for those portions of the machine which experience the most severe stresses as, for example, the work supporting spindle, shiftable tool carriages, and the like.

It is another object of my present invention to provide an improved machine, such as an automatic lathe, in which one or more turning tools are employed to remove peripheral stock from a work piece, for example, a piston for internal combustion engines, and another tool is adapted 10 to make a facing cut on the work. I also propose to employ one or more grooving tools in combination with the turning and facing tools, all of said tools being properly timed so that the portion 15 of the peripheral surface to be acted upon by the grooving tools will be turned prior to the engagement of the grooving tools with the work, and the facing tool will complete a portion of its cutting stroke before the grooving tools act upon the work, whereby to reduce to a minimum the 20 straining torque experienced by the work piece during the cutting operations.

My invention also contemplates a new and improved method of turning a work piece, such as a piston wherein turning and facing tools 25 are arranged to simultaneously act upon the work, the turning tool removing stock from the portion subsequently to be acted upon by one or more grooving tools. After the turning tool has removed the stock from the above mentioned portion of the work piece and the facing 30 tool has advanced a sufficient distance to decrease the torque or strain on the piston, grooving tools begin to cut into the periphery of the work at a speed which is less than the speed of the facing tool, or, in other words, the speed of 35 the grooving tools differs from the speed of the facing tools.

Still another object of my invention is to provide a hydraulic control for tool carriages and the like, which is equipped with an improved main control valve, said valve being automatically shiftable to control the rate and direction of travel of a tool carriage with the utmost convenience and accuracy.

In addition to the above mentioned advantageous characteristics, it is a further object of my invention to provide in a hydraulically controlled machine of the type set forth above, a fluid reservoir which is equipped with means for effecting the gentle return of fluid thereto so as to positively prevent air from entering the reservoir, and consequently prevent air from being trapped within the fluid or oil which is withdrawn from the reservoir.

In addition, I propose to provide in combination with the hydraulic system of control for machine tools, an improved pumping device, in which a novel rotary valve is employed, having structural features which facilitate its lubrication, and which serve as compensating means when the fluid on opposite sides of the valve experiences variation in pressure.

A still further object is to provide a valve as set forth above, which is provided with an arrangement of fluid ports to prevent said valve from experiencing distortion resulting from the extreme fluid pressures to which it is subjected, thereby insuring free running conditions regardless of the intensity of the fluid pressure.

The foregoing and numerous other objects and advantages will be more apparent from the following detailed description when considered in connection with the accompanying drawings, 20 wherein—

Figure 1 is a plan view of an automatic lathe, which is representative of one practical embodiment of my invention, one corner thereof being broken away to enable the insertion of Figures 25 2 and 3.

Figure 2 is an enlarged detailed vertical sectional view of the mechanism for controlling the positioning of the oscillatory guide bar for the front carriage, said view being taken substantially along the line 2—2 of Figure 1.

Figure 3 is a fragmentary horizontal sectional view taken substantially along the line 3—3 of Figure 2.

Figure 4 is a front elevational view of the machine of Figure 1.

Figure 5 is a rear elevational view of said machine.

Figure 6 is an end view thereof as viewed from the left end of Figure 1.

Figure 7 is an enlarged vertical sectional view of the oil reservoir taken substantially along the line 7—7 of Figure 4.

Figure 8 is a vertical transverse sectional view of the machine taken substantially along the line 45 8—8 of Figure 1.

Figure 9 is a detailed vertical sectional view of the oscillatory carriage which supports the grooving tools, said view being taken substantially along the line 9—9 of Figure 1, certain portions 50 of the cooperating elements which would not normally appear in such a section, being shown by dot-and-dash lines.

Figures 10 to 12 inclusive are fragmentary diagrammatic representations to disclose the 55 various positions occupied by the cutting tools during their cycle of operation; Figure 10 disclosing the initial engagement of the front turning and rear facing tools with the work; Figure 11 disclosing the partial completion of the cutting action of said tools and the initial engagement of the grooving tool with the work; and Figure 12 disclosing the completion of the cutting action of all of said tools.

Figure 13 is an enlarged fragmentary elevational view disclosing the mechanism for controlling the operation of the main control valve, said control valve being shown in central vertical section to more clearly illustrate the structural characteristics thereof.

Figure 14 is a vertical sectional view of the main control valve and operating mechanism therefor, taken substantially along the line 14—14 of Figure 13.

Figure 15 is a detailed transverse sectional view

of the main control valve taken substantially along the line 15—15 of Figure 13.

Figure 16 is a transverse vertical sectional view of the valve for controlling the longitudinal movement of the front carriage, said view being taken substantially along the line 16—16 of Figure 14.

Figure 17 is a fragmentary plan view taken substantially along the line 17—17 of Figure 14, disclosing the relative position of the dogs supported at the lower side of the main control valve.

Figure 18 is a diagram disclosing the general arrangement of the fluid circuits incorporated within my improved system of hydraulic control.

Figure 19 is an enlarged central sectional view of a pressure control device coupled with the gear pump.

Figures 20 to 24 inclusive disclose various views of the unitary casting, which provides the bed, 20 spindle support, etc.; Figure 20 being a plan view; Figure 21, a front elevational view; Figure 22, an end view taken from the right end of Figure 21; Figure 23, an end view taken from the left end of Figure 21; and Figure 24 being a rear view.

Figure 25 is a central sectional view of one of the high pressure plunger pumps, disclosing my improved rotary valve construction.

Figure 26 is a transverse sectional view of the valve structure taken substantially along the line 30 26—26 of Figure 25.

Figure 27 is a similar view taken along the line 27—27 of Figure 25.

Figure 28 is likewise a similar view taken along the line 28—28 of Figure 25.

Figure 29 is a transverse sectional view of the pump taken substantially along the line 29—29 of Figure 25; and

Figure 30 is an elevational view of a conventional self-expanding compensator, which is representative of one type of compensator adapted to be employed in combination with my improved rotary tapered valve.

Referring now to the drawings, it will be seen that like numerals have been employed to designate similar parts throughout the various figures.

In order to more readily understand the invention, I shall successively describe the various units which constitute the structural embodiment of my invention disclosed in the drawings.

General lathe structure

The embodiment of my invention disclosed in the drawings includes a unitary casting 40, which in Figures 20 to 24 inclusive is shown detached 55 from any of the lathe elements which it supports. This casting 40 includes a machine base or bed 42, and formed integral with the bed and surrounding same is a trough 44 which serves to collect chips, cooling fluid, and the like. Particular attention is directed to the fact that the bed 42 is cast with a cored chamber 46, Figure 8, and by so forming the bed, its weight is reduced to a minimum. In conventional types of machines with which I am familiar, the machine bed is not formed with a central cored chamber such as my chamber 46. Not only does the presence of the cored chamber within the bed 42 reduce the weight so as to facilitate the shifting of the machine from one position to another, but 70 also reduces the amount of material which is required to form the base. Extending upwardly and formed integral with the base or bed 40 at one end thereof is a headstock section 48. This section 48 is cast in one piece with the bed and 75

provides a support for a rotary work supporting spindle 50. An oil reservoir designated generally by the numeral 52, Figures 4 and 7, is provided within the headstock section 48, and 5 mounted upon a cover plate 54 is a pair of plunger pumps 56 and 58. A partition 59 is cast integral with the bed and extends from the forward portion of the machine downwardly to the rear portion, and at this point communicates 10 with the trough 44. Thus chips, fluid, and the like are directed by this partition to the trough.

Mounted within the cored chamber 46 at one end thereof, Figure 5, is a suitable prime mover or electric motor 60, which is connected, through 15 the agency of a suitable chain 62, with a transmission mechanism 64. This transmission mechanism 64 includes a suitable clutch mechanism 66 which serves to control the delivery of power to the work supporting spindle 50 through suitable 20 gearing shown in Figure 6. It will also be noted that in Figure 6 the spindle 50 is directly coupled through the agency of suitable gearing with the plunger pumps 56 and 58. Mounted upon the bed 40, Figure 5, is a gear pump 68, 25 which is continuously driven from the transmission mechanism 64 through the agency of a suitable chain or belt 70. This gear pump 68 is preferably of the type disclosed in my co-pending application, Serial No. 430,868, filed February 30, 1930, which has since matured into Patent No. 1,912,737, and is adapted to supply fluid for rapid traverse purposes, while the plunger pumps 56 and 58 are preferably of the variable displacement type disclosed in my co-pending application, Serial No. 430,867, filed February 24, 1930, 35 which has since matured into Patent No. 1,989,117.

A tailstock 72, Figures 4 and 5, includes a rotary center 74 mounted within a split bearing 76, said bearing being supported and formed integral 40 with a base 78. The base 78 is adjustably supported by the main machine bed 40.

A front tool carriage, denoted generally by the numeral 80, is mounted upon a horizontally and longitudinally shiftable bar 82, which is supported 45 within the bed 40, and a rear tool carriage, denoted generally by the numeral 84, is adjustably mounted upon the rear upper surface of the bed 40 and is adapted to be reciprocated transversely of the axis of the work supporting spindle 50.

50 Front tool carriage

The front carriage 80 includes an oscillatory frame or support 86 which is clamped upon the oscillatory bar 82, Figure 8. A slide 88 is adjustable 55 on the frame 86 toward and away from a work piece 90 disclosed by dot-and-dash lines in Figure 8, and adjustably mounted upon this slide 88 is a tool holder 92 which carries a cutting tool 94. At this point it should be understood that the 60 spindle 50 is normally driven in a clockwise direction as viewed in Figure 8, so that the cutting force acts upwardly against the front tool 94.

Movement of the tool carriage 80 toward the work piece is accomplished through the agency 65 of a hydraulic actuator 96, which includes a piston 98 vertically reciprocable within a cylinder 100. A piston rod 102 extends upwardly and supports the free extremity of an oscillatory guide bar 104 which serves to guide a roller 105 carried 70 by the frame 86. The opposite extremity of this guide bar 104 is pivoted within a block 106, Figures 2, 3, and 4. This block is adapted to be vertically adjusted within a guide 108 by means of a screw 110. Thus the pivot 112 of the bar 104 75 may be vertically shifted in accordance with the

type of work piece to be acted upon. If the guide bar 104 occupies a horizontal position when the actuator piston 98 occupies its uppermost position and longitudinal movement is imparted to the carriage 80, the tool 94 will move parallel with the axis of the work piece. For tapered cutting, however, the pivotal point 112 may be vertically adjusted. Longitudinal movement is imparted to the front carriage 80 by a hydraulic actuator indicated generally by the numeral 114, Figure 4, 10 which includes a cylinder 116 and a piston 118, said piston being coupled with the left extremity of the oscillatory bar 82 by means of a piston rod 120. From the foregoing it will be apparent that the hydraulic actuator 96 serves to move 15 the tool 94 into cutting position with respect to the work piece 90, Figure 8, and the hydraulic actuator 114, Figure 4, serves to impart movement to the tool longitudinally of said work piece. Obviously the actuator 96 is designed to move the 20 front carriage during the cutting operation at both rapid and feeding rates.

Rear tool carriage

The rear tool carriage 84, Figures 1, 5, 8, and 9, 25 includes a slide 122 which is shiftable in a direction transverse to the spindle axis by means of a hydraulic actuator 124, which includes a cylinder 126, a piston 128, and a piston rod 130, which is coupled to the rear extremity of the slide 122. 30 The cylinder 126 is formed integral with a frame 132, and this frame is adjustably secured to the bed 40, Figure 8. The slide 122 carries a tool holder 134, which supports a cutting tool 136, 35 said tool serving to make a facing cut upon the work piece 90 (see diagrammatic disclosures in Figures 10 to 12 inclusive).

The rear tool carriage 84 also includes an oscillatory frame 138 which is pivotally supported by a bar 140 mounted within the frame 132, Figures 40 8 and 9. This oscillatory frame 138 adjustably supports a tool holder 142, which is adapted to carry a set of grooving tools 144. Movement of these grooving tools toward and away from the work piece 90 is accomplished by oscillating the 45 frame 138 about the bar 140, and the movement of the grooving tools toward the work is accomplished by means of a pivoted cam member 146 carried by the slide 132. When a surface 148 of the cam member 146 engages a roller 150 carried 50 by the frame 138, said frame is swung so as to move the grooving tools 144 into cutting relation with respect to the work piece. It will be apparent that no forward movement will be imparted to the grooving tools until the facing tool 138 55 has been shifted a predetermined distance. In other words, the rear carriage is so arranged that the facing cut on the work piece is partially completed before the grooving tools are caused to function. This particular arrangement of the 60 rear carriage cutting tools has a very practical application in connection with the turning of pistons of internal combustion engines. It will be apparent that the greatest torque is experienced by the piston as the tool 136 makes its 65 initial facing cut, and that as this tool approaches the center of the face, the torque or stress upon the piston is materially reduced. By employing my improved structural arrangement, the cutting action of the grooving tools is delayed until the stress to which the piston is subjected as a result of the cutting action of the tools 136 and 94, is materially reduced, thereby 70 overcoming serious difficulties which have heretofore been experienced in instances where the 75

initial grooving and facing cuts have been made simultaneously. This feature of the invention will be more readily appreciated from the description which is to follow. It will be seen that 5 the entire rear carriage 136 may be shifted longitudinally with respect to the work supporting spindle by merely loosening clamping nuts 152, Figure 1, and then shifting said carriage along ways 154 provided within the machine bed 40.

10 The slide 122 of the rear tool carriage is mechanically coupled with a rotary valve control mechanism 156 mounted on the front side of the machine bed. This mechanical coupling includes a rack 158 shiftable with the slide 122, which 15 meshes with the pinion 160, Figure 9, keyed to a shaft 162. This shaft 162 extends longitudinally of the machine, and is coupled by means of mitre gears, Figure 1, with a transverse shaft 164. The extremity of the shaft 164, which 20 terminates at the front of the machine, carries a gear 166, Figures 4 and 13, and this gear meshes with a companion gear 168, Figures 13 and 14. Thus, it will be apparent that, when movement is imparted to the rear slide 122 toward the work piece, a clockwise movement will 25 be imparted to the gear 166, and a counter-clockwise movement to the companion gear 168, as viewed in Figure 13.

30 *Main valve and rotary control mechanism therefor*

The rotary valve control mechanism 156 is 35 designed to timely control the shifting of a main control valve mechanism designated generally by the numeral 170, Figures 14 to 18 inclusive, which is mounted on the front side of the machine in a convenient position to be actuated by the operator. In order to simplify an understanding of the structural and functional characteristics of the main control valve 170 and the 40 rotary control mechanism 156 therefor, I shall describe these parts in connection with the hydraulic system of control which governs the timed or synchronized movements of the various lathe 45 elements such as the tool carriages and the fluid pumps. It will be seen that the valve mechanism 170 includes a casing or housing 172, which supports a pair of reciprocable valve members 174 and 176, which are coupled by means of a 50 connecting element 178, Figure 13. It will also be seen that the rotary control mechanism 156 includes a plate 180 provided with a T-slot 182, which is adapted to adjustably receive a plurality of dogs 184, 186, 188, 190, and 192. This 55 plate 180 is rotatable with the gear 168 and is supported by a stubshaft 194.

Assume that a work piece such as the cylindrical member 90 shown by the dot-and-dash lines in Figure 8 and by the full line in Figures 60 10 to 12 inclusive, is mounted within the spindle 50, and that the front carriage 80 occupies its limiting downward position, and the rear carriage slide 122 occupies its rear position. When 65 the carriages occupy these positions their respective tools 94, 136, and 144 are removed from the work piece. Assume further that the valve members 174 and 176 occupy the neutral position shown in Figure 13, and that the dogs on the rotary plate 180 also occupy the relative positions shown in Figure 13. The prime mover or 70 electric motor 60 is now operating and causes the gear pump 68 to be activated. The clutch mechanism 66 is positioned so as to disconnect the work supporting spindle 50 from the prime mover, and thus the plunger pumps 56 and 58

are not activated. The operator shifts a control handle 196, Figure 1, to the left, and said handle being connected with the valve members 174 and 176 by an arm 198, causes said valve members to be shifted to the right, Figure 13. 5 In this shifted position fluid from the gear pump 68, Figure 18, is directed through a distributor mechanism 200 (later to be described) and thence through a pipe line 202, Figures 13 and 15, which 10 communicates with a passage 204 of the valve 174 and a passage 206 of the valve 176. The valve passage 204 is now in communication with a pipe line 208, while the passage 206 is closed to a pipe line 210, which connects with the valve mechanism. Fluid within the pipe line 208 15 passes into the lower end of the cylinder 100 of the hydraulic actuator 86, Figure 18, thereby causing the piston 98 to be shifted upwardly. This results in the movement of the front tool 94 toward the work piece and in the passage of 20 fluid from the cylinder 100 through a pipe line or conduit 212, a check valve 214, and a conduit 216 which is connected with a hydraulic actuator 218, the latter serving to control the clutch mechanism 66. Fluid thus introduced within the 25 actuator 218 causes a piston 220 to be shifted to the left, Figure 18, right, Figure 5, within a cylinder 222, and this establishes driving connection between the prime mover 60 and the 30 work supporting spindle 50. Fluid from the hydraulic actuator 218 passes through a conduit or pipe line 224 into the rear extremity of the cylinder 128 of the rear tool actuator 126. It will thus be apparent that the shifting of the valve members 174 and 176 to the right, Figure 13, 35 causes the front tool 94 and the rear tool 136 to be moved at a rapid rate into cutting position with respect to the work piece.

The advancement of the rear carriage slide 122 causes the rotary dog support 180 to be shifted in a counter-clockwise direction, as viewed in Figures 4 and 13. The dog 182 is eventually moved into engagement with a finger 226 carried at the lower end of a shaft 228, which supports the valve control handle 196, and this causes the valve members 174 and 176 to be returned to the neutral position shown in Figure 13. The plunger pumps 56 and 58 which were automatically actuated upon the establishment of driving connection between the spindle 50 and the prime mover 60, now serve to deliver fluid at high pressure through pipe lines or conduits 230 and 232 respectively, Figure 18. This causes the advancement of the rear tool 136 at a feeding rate across the face of the work piece 90 and the longitudinal travel at a feeding rate of the front tool 94 along the periphery of said work piece. Fluid from the advancing side of the actuator piston 128 is directed through a line or conduit 234 back to the plunger pump 58, and fluid from the advancing 60 side of the actuator piston 118 passes through a conduit 236, a front carriage control valve 238 and a conduit 240 back to the intake side of the pump 56. It will be observed that the dog 182, upon engaging a finger 242 carried by a shaft 244 65 of the valve 238, Figure 13, causes said valve to establish communication between the conduits 236 and 240 at the desired interval as to timely control the longitudinal travel of the front tool carriage.

70 It will be noted, particularly in Figures 13 and 14, that the rotary plate 180, together with the dogs supported thereby, is detachably supported through the agency of the stub shaft 194. The dogs on the plate may be supported to effect a 75

predetermined cycle of operation corresponding with the particular type of work to be done. If the machine is to be used for the performance of a different cycle of operation, it has been found 5 advantageous in certain instances to detach the plate and replace it with another one having the dogs thereon positioned in accordance with the new cycle of operation to be performed. This avoids the necessity of employing the operator's 10 time to set up the dogs in proper position each time the machine is used for a different type of work piece. The plates having the dogs properly mounted thereon can be kept in stock and used whenever occasion demands. This arrangement 15 also enables the machine to be operated by persons not particularly skilled in setting up automatically operable machine tools.

Attention is now directed to the grooving tools 144 which, during the initial advancement of the 20 facing tool 136, remain stationary. However, when the cam surface 148 of the pivoted cam member 146, Figure 8, carried by the rear tool slide 122, moves into engagement with the roller 150, the oscillatory frame 138 swings forwardly 25 so as to carry the grooving tools into operative association with the periphery of the work piece. The movement of the grooving tools is timed so that the tool 136 will have completed a substantial portion of its facing cut before the grooving 30 tools actually begin to cut. By delaying the operative functioning of the grooving tools, I avoid the necessity of subjecting the work piece to the severe stresses which would otherwise result if said tools were initially brought into simultaneous engagement with the work piece. Furthermore, the delay in moving the grooving tools permits the front tool 94 to make a peripheral cut across the surface of the work piece previous to the cutting action of the grooving tools. In other words, 35 the front tool 94 removes stock from that portion of the peripheral surface to be acted upon by the grooving tools before said grooving tools start to cut. Obviously the timing of the movement of the grooving tools will be determined by the nature of the cam surface which engages the roller 150, and this in turn will be dependent upon the type of work which is being operated upon. It will be seen that I provide an adjusting screw 146a on the pivoted cam member 146, which 40 serves as a means for accurately positioning said cam member. By employing the above described mechanism, the speed of movement of the grooving tools may be considerably slower than the speed of the facing tool. In other words, the 45 speed of the grooving tools is different from the speed of the facing tool, the speed of said grooving tool in a sense being independent of the speed of the facing tool, inasmuch as the contour of the cam surface will determine the speed at which 50 the oscillatory grooving tool carriage is moved.

The feeding stroke of the hydraulic actuators 114 and 124 continues until the dog 188 is moved into engagement with the outer end of a valve member 246, Figure 13. Shifting this valve member 55 to the left against the action of a coil spring 248 effects a sudden establishment of communication between a valve chamber 252 and the fluid reservoir 52. In other words, when the valve member 246 shifts to the left, communication between a passage 254 and the chamber 252 is 60 closed, and fluid from the chamber 252 flows unrestrictedly through a central valve passage 256, a radial port 260, and a pipe line or conduit 262. The sudden release of the fluid from the chamber 65 252 enables the normal fluid pressure within an

opposite valve chamber 264 to cause the valve members 174 and 176 to be suddenly shifted to the left. In this position said valve members initiate a flow of fluid in the reverse direction to the hydraulic actuators 124 and 114. Thus, in 5 this reverse position fluid from the gear pump 68 passes through the valve ports 204 and 206 into pipe lines 266 and 268 respectively, Figures 13 and 18. Fluid from the pipe line 268 passes into the forward end of the actuator cylinder 126 10 and also causes the sudden shifting of the clutch controlling actuator piston 220 to the right, Figure 18, thereby disconnecting the source of power from the spindle and plunger pumps. Fluid from the pipe line 266 is directed into the pipe line 236 and thence into the left end of the actuator cylinder 116. It will thus be apparent that the front tool carriage is moved at a rapid rate in a reverse direction, namely, to the right, Figures 20 4 and 18, and that the rear tool carriage is similarly moved in a reverse direction, namely, to the right, Figure 8. The dog 190 carried by the rotary support 180 eventually engages a finger 270 oppositely disposed from the finger 242, thereby closing the valve 238, and the dog 184 is 25 eventually moved into engagement with a finger 272, Figures 14 and 17, so as to cause the valve members 174 and 176 to be again shifted to their neutral position. This completes the cycle of 30 operation, which may be repeated by merely shifting the control handle in the manner just described.

It will be noted that when the valve members 174 and 176 occupy their neutral position, fluid from the rapid traverse or gear pump 68 circulates through radial ports 214 and 216 respectively, which communicate with central valve passages 278 and 280, Figure 13. These central passages open into the valve chamber 264, which communicates with the opposite valve chamber 250 through a longitudinal connecting passage 282, Figure 15. It will also be apparent that the instant that the valve members 174 and 176 are suddenly shifted to their reverse position, namely, to the left, Figure 13, the pipe line 208 becomes a return line for the hydraulic actuator 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 and 116 occupy their neutral position shown in Figure 13, they render the gear pump functionally inoperative for propelling purposes and provide an effective seal for the high pressure circuit. In other words, when the plunger pumps 56 and 58 function to propel their respective hydraulic actuators at a feeding rate, said pumps are connected within closed circuits, the fluid on the discharge side of the actuator 10 piston being sufficient to charge the plunger pump. In fact, the fluid from the advancing side of these actuator pistons provides the sole charging fluid for the plunger pumps.

For a more detailed description of the charging action of the actuator pistons 118 and 128, reference is made to my co-pending applications relating to automatic lathes, Serial No. 439,306, filed March 27, 1930, and Serial No. 481,742, filed September 13, 1930.

20. Plunger pump construction

Particular attention is directed to the structure of the plunger pumps 56 and 58, and in this connection special reference is made to Figures 25 to 29 inclusive. The pump, as set forth above, is of the general type disclosed in my above mentioned co-pending application, but incorporates certain novel features which are not shown in said co-pending application. Both of the pumps 30 56 and 58 are identical in construction, and therefore the description of one will suffice for a description of the other. Each of these pumps includes a central casing 294, an end casing section 286 secured thereto by means of bolts 35 288, and an oppositely disposed end section or support 290, Figure 25. This support 290 houses a plurality of radial reciprocable plungers or pistons 292, the inner ends of which engage the curved surfaces of pivoted fingers 294. These 40 fingers in turn rest upon the peripheral surface of a driving ring 298 rotatably supported upon an eccentrically adjustable driving member 296. By displacing the center of the ring 298 from the center about which the pistons 292 radiate, and 45 then rotating said ring, the pistons are successively urged outwardly to compress fluid in chambers 300. The eccentric adjustment of the driving member 296 is controlled by means of suitable adjusting mechanism, which includes 50 a longitudinally shiftable member 302, which is provided with a projection 304 extending into a companion recess provided in the driving member 296. This projection 304 is inclined with respect to the axis of rotation, and when longitudinal movement is imparted to the member 302 55 in response to the turning of a cap 306, the driving member 296 is laterally shifted within a driving sleeve 308.

I provide a rotary tapered valve 310 which is 60 mounted within a companion bushing 312. This valve is adapted upon rotation to control the flow of fluid toward and away from the piston chambers 300. Thus fluid introduced from the pipe line 294 enters a chamber 314, and from this 65 chamber is directed through a central passage 316, which communicates with a peripheral valve port 318. This valve port 318 successively registers or communicates with radial ports 319 in the bushing 312, which connect with passages 70 320 provided in the support 290. This peripheral valve port 318 is timed so as to communicate with the piston chambers 300 during the intake stroke of their companion pistons 292, while a similar peripheral valve port 322 is timed to communicate with those piston chambers 300, which

are companion to the pistons experiencing their outer or compressing stroke. Thus fluid under pressure is directed from the passages 320 through a peripheral passage 324 in the bushing 312, and this passage in turn communicates with a radial port 326. Fluid under pressure from these ports 326 is directed through the peripheral valve port 322 and into a passage 328, Figures 25 and 27, which communicates with an annular valve passage 330. It should be noted that this annular passage 330 is slightly enlarged at the point designated by the numeral 332, Figure 25, and fluid from this annular passage passes outwardly through the pipe line 290 into the rear extremity of the hydraulic actuator 124. Likewise, fluid under pressure in the pump 58 passes outwardly through the pipe line 232 to the right end of the hydraulic actuator 118 and lower end of the actuator 96.

By having the low and high pressure peripheral ports arranged in the manner described above, I am able to positively preclude the valve from experiencing any distortion which might otherwise result from the subjection of the valve to these pressures. It will be seen that the high 20 pressure experienced by the valve in the peripheral port 322 is counteracted or neutralized by the fluid pressure acting within the annular passage 330 adjacent its enlarged portion 332, Figures 25 and 27. That is to say, any tendency of the 30 fluid pressure acting on one side of the valve to cause said valve to bind or become distorted, is prevented by the neutralization of pressures on opposite sides of the valve. This neutralization or balancing of the valve is particularly important when the fluid pressure reaches a substantial amount, as, for example, pressures in excess of five hundred pounds per square inch. It should be understood that it is very important to have the tapered valve freely rotatable so as 40 to prevent wear and to maintain a very close, accurate running fit.

It should also be noted that toward the larger end of the valve 310, the pressures acting thereon neutralize one another. Thus, for example, the 45 high pressure fluid within the upper three radial ports 319 shown in Figure 26 act downwardly upon the valve, while the pressure in the two lower radial ports 319 and the peripheral port 318 act upwardly, thereby effecting a substantially balanced condition. Attention is also directed to the fact that by having the low pressure peripheral port 318 spaced axially from the high pressure peripheral port 322 and the communicating annular port 330 the possibility of 55 slippage of fluid between high pressure and low pressure ports is prevented. It will be seen in Figure 28 that the upper three radial passages or ports 319, as well as the peripheral port 322, contain high pressure fluid, while the two lower 60 radial ports 319 contain low pressure fluid. There is sufficient circumferential distance between the low pressure ports 319 and the high pressure ports 326 to positively prevent any slippage of fluid between them. Likewise, in Figure 26 it 65 will be seen that sufficient circumferential distance is provided between the radial ports 319 containing the high pressure fluid and the ports 318 containing the low pressure fluid to prevent such slippage. In other words, by axially spacing the high and low pressure peripheral ports in the manner described, I am able to reduce to a minimum the possibility of fluid slippage between high and low pressure valve ports. Obviously the reduction of slippage is an extremely important 75 factor in the proper functioning of the valve.

tant factor in connection with pumping devices of the type disclosed herein, because, in the first place, fluid slippage causes serious increases in fluid temperatures, and, in the second place, results in a decided decrease in mechanical and propelling efficiency. Furthermore, pumps such as the pumps 56 and 58, are employed in closed circuits which are so arranged that the fluid discharged by the pump acts against one side of the actuator piston and the fluid displaced by the advancing side of the actuator piston is the sole charging medium introduced within the intake side of the pump. Hence, any slippage of fluid within the system would tend to seriously affect the propelling effectiveness or efficiency of the pump.

Attention is now directed to a pair of grooves 334 and 336 provided at the larger end of the tapered valve 310. The groove 334 communicates with the central valve passage 316 and as such serves to return fluid which might slowly work its way along the surface of the valve to the left, Figure 25, back to the central passage 316. It should be understood that the tapered construction of the valve is such as to provide a fluid seal within the closed circuit described above, and positively prevents the leakage or slippage of fluid longitudinally of the valve toward its larger end to an extent that would impair the efficient functioning of the closed circuit.

To insure proper lubrication of the valve surface extending to the left of the groove 334, Figure 25, I provide the groove 336. This groove 336 is continuously connected through a conduit or pipe line 338 with a passage or port 340 of the distributor mechanism 200, Figures 18 and 19. A similar pipe line or conduit 338 communicates with the rotary valve in the pump 56. A portion of the fluid under pressure from the gear pump 68 is directed through the pipe line or conduit 338 and thereby provides a predetermined amount of fluid pressure within the groove 336. Under normal operating conditions the pressure of the fluid within the groove 336 exceeds the pressure of the fluid in the groove 334, thereby preventing the flow of fluid from the groove 334 to the left, but providing a fluid film along the surface of the valve positioned to the left of the groove 334, Figure 25. In other words, any tendency for a slight migration of fluid along this surface would be from the groove 336 toward the groove 334. Thus it will be apparent that one of the primary functions of the groove 336 is to present a fluid body under increased pressure at the point where the fluid from the groove 334 might not in some instances provide the required amount of lubrication along the surface of the rotary valve at its larger end.

It should also be understood that the groove 336 provides a compensating means to take care of fluctuations or variations in fluid pressure within the hydraulic system of control. Thus, for example, if the pressure of fluid within the low pressure side of the system is suddenly increased above the pressure of the fluid within the groove 336, said groove will permit a compensating flow or migration of fluid from the groove 334 into the groove 336. Such a sudden increase in fluid pressure within the low pressure side of the system takes place when the main control valves 174 and 176 are suddenly shifted from rapid traverse to feed. That is to say, certain of the valve ports within the main control valve 170 are suddenly restricted so as to effect a momentary building up of fluid pressure within

the low pressure circuit, and in this instance the groove 336 provides a relief or compensating means. Furthermore, the expansion and contraction of the fluid are similarly compensated for by the groove 336.

At this point it should be understood that my particular rotary valve construction with its compensating grooves has a very practical application when used in connection with various types of material working apparatus other than lathes.

For example, a valve of this type used in connection with a milling machine in which "climbing milling" is performed has a very practical application. By "climbing milling", I mean the milling of a work piece by moving the work piece

in the same direction as the rotation of the milling cutter as distinguished from moving a work piece against the rotation of the cutter.

In such instances a pressure may be built up on the advancing side of the actuator piston which is in excess of the pressure on the trailing side as compared with the opposite conditions which exist in the actuator pistons when used in the machine described in the present application.

The compensating groove 336 of the valve in such instances provides a very practical and efficiently operable means for bringing about an automatic or self-adjustment of fluid conditions within the high and low pressure side of the circuits, and, in addition, performs its

function of insuring proper lubrication of the valve at its larger end. In fact, my improved valve construction equipped with the particular arrangement of the peripheral valve ports and the peripheral grooves described above presents

a very positive fluid seal within a closed circuit, and at the same time insures longevity of the valve and its bearing. When it is appreciated that pumps connected with machines such as automatic lathes, milling machines, boring machines,

and the like, are subjected to substantially continuous operation day in and day out, the problem of insuring a true running fit of the tapered valve over an extended period of time is of the utmost importance.

To control the fluid pressure within the groove 336, I provide the distributing means or mechanism 200, which includes a suitable casing 342 which is adapted to be secured within the discharge opening 344 of the gear pump, Figures 18

and 19. An adjustable plug 346 is provided within the casing 342 and the shifting of this plug serves to vary the pressure conditions in accordance with the pressure which is required within the groove 336. Obviously the pressure

within the groove 336 is normally above the pressure of the fluid which passes from the gear pump 68 through the pipe line 202 into the main control valve 170.

In order to automatically take up any slight wear in the valve 310, I have inserted a compensator of conventional design indicated generally by the numeral 348, Figures 25 and 30.

The particular type of compensator 348, which I have shown for the purpose of illustrating one practical device which may be employed, is a design commonly referred to in the trade as "Wyr-omat-ick Compensator". For a clear understanding of the present invention it will not be necessary to enter into a detailed discussion

with this conventional compensator. It will suffice to say that it includes a pair of adjacently positioned rings 350 and 352, said rings being provided with cooperating cam surfaces and a locking pin or key 354. These rings automatically

expand as a result of means provided within the device for effecting relative rotation between the rings, and when the separation becomes great enough to clear the locking pin or key 354, relative rotation of the rings will occur so as to take up any slight wear in the valve. This device is designed to take up less than .0005" axial adjustment. It will be seen that this compensator 348 is inserted between the valve bushing 312 and an anti-friction bearing 356 which is clamped by means of a collar 358 mounted upon the threaded split end of the valve member 310. Obviously other forms of compensator devices for automatically taking up wear may be employed in combination with rotary valves without departing from the spirit and scope of my invention.

In order to preclude the introduction of air within the fluid body of the hydraulic system, I have arranged the reservoir 52 in such a manner as to enable the calm or undisturbed entrance of fluid within said reservoir. It will be apparent from Figure 7 that the reservoir 52 includes an outer casing 360 and an inner casing 362. Fluid which is returned to the reservoir through a pipe line 364, which connects the reservoir with the valve chamber 250, Figure 13, passes through a fixed, restricted orifice 366, Figure 7. It will be seen that this orifice is bell-mouthed on its entrance side and tapers to a larger opening on its egress side. Fluid passes from this orifice through an inclined conduit 368 and is directed against a substantially conical surface 370, which has its apex at 372. This apex 372 is positioned adjacent the mouth of the inclined conduit 368, and fluid from the conduit flows gently along the conical surface 370, which blends into the side walls of the inner reservoir, thereby preventing the fluid from being churned or swirled to such an extent as to develop air pockets or bubbles. In this manner the sudden ingress of the fluid is interrupted so as to preclude the agitation or stirring of the fluid body. In other words, a very calm, undisturbed entrance of the fluid within the inner casing 362 takes place as a result of the structural arrangement just described. Fluid from the inner tank 362 overflows into the casing or tank 52. The slow overflow of fluid also contributes toward maintaining the fluid body which is withdrawn from the outer casing, free from air bubbles. To maintain a hydraulic circuit free from air bubbles or pockets is of extreme importance, particularly in connection with hydraulic systems which are employed for moving machine tools and the like. A very small amount of air within a circuit is sufficient to seriously impair the operating efficiency thereof. It should be understood that by employing my hydraulic system of control, I am able to govern the shifting of the tool carriages within a fraction of a thousandth of an inch, and to accomplish this I have not only arranged the hydraulic actuators, pumps, and connecting conduits in such a manner as to provide a closed circuit, but have provided means for positively preventing the introduction of air within the circuit. Devices with which I am familiar have been employed heretofore to remove air from the system, but my improved arrangement must be differentiated therefrom inasmuch as I propose to prevent the air from initially entering the system, thereby avoiding the necessity of removing air from within the conduits forming a part of the hydraulic system of control. The mechanism just described for preventing air from entering the hydraulic system is similar in some respects

to the system set forth in my co-pending application relating to Hydraulic system, Serial No. 456,571, filed May 28, 1930, which has since matured into Patent No. 1,985,748 wherein I have disclosed a modified reservoir structure for effecting the calm entrance of fluid. Experience has shown that the inclusion of air within a hydraulic system not only causes pulsating effects resulting from the presence of air pockets, but also causes the fluid to disintegrate. This is particularly true when air is trapped within a fluid, such as oil.

Statement of operation

From the foregoing it will be apparent that in operating the above described apparatus, the work piece 90 is mounted upon the work spindle 50. The prime mover or electric motor 60 is activated so as to cause the gear pump 68 to operate. Fluid from the gear pump circulates through the conduit or pipe line 202, the main control valve 170, and the return pipe line 364. The operator now shifts the control handle 186 to the left, Figure 1, thereby causing the valve members 174 and 176 to be shifted to the right, Figure 13. In this shifted position the hydraulic actuator pistons 98 and 128 are shifted so as to effect the rapid movement of the front tool 94 and the rear tool 136 toward the work piece. Contemporaneously with the rapid movement of these tools, the hydraulic actuator 218 shifts the clutch so as to mechanically connect the spindle 50 and the plunger pumps 56 and 58 with the prime mover. When the dog 186 engages the finger 226, Figures 14 and 17, the valve members are returned to their neutral position, thereby cutting off the rapid traverse or gear pump 68 and connecting the plunger pumps 56 and 58 in closed circuits for imparting feeding movements to the tool carriages. The dog 186 also causes the opening of the valve 238, thereby enabling the front tool carriage to be moved longitudinally of the work piece. Thus the front tool 94 makes a peripheral cut across the surface of the work piece, while the tool 136 makes a facing cut. When the tool 136 has completed a portion of its cutting stroke, the grooving tools 144 are brought into operative association with the work piece. Upon the completion of the cutting stroke of all the tools, the dog 186 shifts the valve 246, thereby unbalancing the fluid pressure within the main control valve 170. This causes the sudden shifting of the valve members 174 and 176 to the left, and throws the hydraulic system of control into reverse. It also causes the clutch actuator to disengage the clutch, thereby rendering the plunger pumps functionally inoperative for propelling purposes. In this manner the tool carriages are returned to their initial starting position, and when the dog 186 engages the finger 272, the valve members 174 and 176 are returned to their neutral position.

Summary

From the foregoing description it should be apparent that my invention presents numerous advantageous structural features. The manner in which I have cast the machine bed, headstock, etc., in a single piece presents a marked improvement over structures which, to my knowledge, have been employed heretofore. Not only have I been able to appreciably reduce the aggregate weight of this apparatus as compared with conventional devices so as to enable the convenient

movement or shipment from one place to another, but I have also produced a bed having the increased rigidity and sturdiness which are required to render a machine capable of employing 5 the more recently developed tools constructed of alloys, such as tungsten carbide and the like. These tools have been designed for high speed cutting in materials, such as cast iron, etc., but in order to render them efficient in operation, a 10 machine of unusual strength and rigidity must be provided. This fact is particularly true in connection with machines of the automatic type, such as the automatic lathe described above. It should be noted that by having this unitary or 15 integral casting construction, I eliminate vibrations which, of necessity, present themselves when numerous parts are bolted or in other ways secured together. Furthermore, by having my particular unitary bed and headstock construction, I preclude the possibility of misalignment 20 of machine parts, which frequently occurs in machines of conventional design during the shipment from the point of manufacture to the shop in which the machine is to be used. A very slight 25 loosening or shifting of the supporting elements of the machine is sufficient to effect a misalignment, which must, in many instances, be corrected before the machine can actually be put into production work. With the idea of overcoming 30 these difficulties, I have produced a machine in which the work supporting spindle, for example, is mounted within a headstock support formed integral with the unitary bed of the machine. This unitary bed, in turn, supports the carriages, 35 and therefore I am able to maintain absolute alignment between the tools supported by the carriages and the work piece supported by the spindle.

Particular attention is again directed to my 40 improved method of performing cutting operations upon elements, such as pistons wherein a peripheral and facing cut is taken, and when the facing stroke of the rear tool has been partially completed, the grooving operation is begun. In 45 this way I do not subject the piston to the excessive torque or load which would obviously result in the event that both the facing, turning, and grooving tools were brought into simultaneous engagement with the work piece at the beginning 50 of their strokes. As the facing tool moves inwardly, the load or torque experienced by the piston is materially decreased. Furthermore, it is decidedly advantageous to make the peripheral or turning cut by the front tool before the grooving 55 tools are brought into operative association with the work. The above described method enables the production of parts, such as pistons, to be speeded up, and at the same time maintains extreme accuracy in the work produced.

60 It should also be clear that my improved hydraulic system of control has a very practical application in connection with machines of the type described. By arranging the rotary valve in the plunger pumps in the manner described, a true 65 running fit is continuously maintained, thereby insuring a positive fluid seal, a reduction in wear, and a positive prevention of increased fluid temperatures. The rotary valve is maintained substantially in balance with no pressure tending 70 to urge the valve in any particular direction. In this way the valve may be rotated with minimum power and for an extended period of time. The automatic means for taking up wear in the valve also contributes materially toward the efficient 75 functioning thereof. The annular groove 336

cooperates with the groove 334 in positively insuring proper lubrication of the valve at its larger end, and in compensating for any variations in fluid pressure which frequently result. When the pump is employed in the particular type of circuit disclosed, an increase in fluid pressure within the low pressure side of the circuit is occasioned when the main control valve is shifted so as to instantaneously restrict its ports, and the sudden building up of this pressure is compensated for 10 by the arrangement of the grooves within the valve. The distributor mechanism provides a very convenient means for varying the pressure within the groove 336 to accommodate the particular conditions under which the pump is operating. Obviously this type of valve is by no means limited for use in connection with circuits applied to lathes, but applies also to a circuit which may be employed in connection with various types of material working apparatus, in 15 which a hydraulic actuator is employed to propel a machine carriage.

It will be noted that the actuator piston 118 is provided with a piston rod 120 on each side thereof, whereas the actuator piston 128 is provided 20 with a piston rod on only one side thereof. Obviously the volume of fluid displaced from the advancing side of the piston 118 will be equal to the volume of fluid received on the opposite side of the piston, whereas the volume of fluid 25 discharged from the advancing side of the piston 128, as it moves forwardly, will be slightly greater than the volume taken in on the opposite side of the piston due to the presence of the piston rod. To take care of this slight volumetric difference, I provide a vent 268, Fig. 13, which is in continuous communication with the conduit or pipe line 268. This vent is similar in functional characteristics to the vents disclosed in one of my above mentioned copending applications, 40 Serial No. 439,306, filed March 27, 1930, and a detailed explanation thereof in the present application is not necessary to a clear understanding of the invention. It will suffice to say, however, when a piston is equipped with a piston rod on either side thereof, as shown in the hydraulic actuator 114, a vent, such as the vent 268, is not 45 needed. Both forms of pistons are disclosed in the present application to show that my invention is not limited to any particular form of actuator construction, but is capable of employing pistons equipped with rods on one or both sides thereof. In this connection attention is again directed to the improved fluid compensating arrangement, with which the rotary valve 310 is equipped. 50 By having the grooves 334 and 336 in the valve, a unique sealing of the fluid is obtained, and by this arrangement any change in fluid volume, due to increased heat, etc., is compensated for, and the presence of fluid between the grooves positively prevents any fluid from leaving the system when said system is functioning under normal conditions. Attention is also directed to the fact that capillary action along the surface between the grooves 334 and 336 contributes to the sealing 55 effectiveness of the rotary valve.

My invention is not limited to a machine equipped with a single grooving tool, but contemplates the use of a plurality of grooving tools where the nature of the work requires such a construction. In other words, the front tool carriage is adapted to be equipped with a tool differing in form from the turning tool 94. A device constructed in accordance with the teachings of my invention may be designed to meet 60

various problems relating to the grooving of work pieces, such as pistons. It has heretofore been the practice in some instances in the manufacture of pistons to tin the outside diameter of a grey 5 iron piston, and, subsequent to this operation, a roughing and then a finishing grooving cut is made. It will be apparent that a machine constructed in accordance with the teachings of my invention is readily adapted to be employed in 10 such instances.

By causing the returned fluid to be directed against the conical surface 370 within the fluid reservoir and then permitting the fluid from the inner reservoir to slowly overflow into the outer 15 reservoir, I am able to positively prevent air from entering the fluid at this point. By employing such an arrangement with the sealed or closed fluid circuit just described, the conduits thereof will remain free from air pockets. This will enable 20 the tool carriages to be moved without the slightest degree of pulsation and to be accurately timed in their movements within a fraction of a thousandth of an inch.

The foregoing statements regarding the functioning of my improved lathe structure have been substantiated by actual work in the field. Machines constructed in accordance with the teachings of my invention have been subjected to severe actual working conditions in the shop and 30 have materially increased shop production.

Obviously numerous changes and modifications may be made in certain of the structural features described above without departing from the spirit and scope of my invention, said invention being limited only by the scope of the 35 appended claims.

Having thus described my invention, what I claim as new and desire to secure by Letters Patent is:

40 1. In material working apparatus of the class described, a unitary bed including a base formed integral therewith and adapted to rest upon the floor and having a spindle supporting section formed integral therewith and extending upwardly therefrom, a rotary spindle in said section, a shiftable carriage mounted upon said unitary bed, a chip receiving receptacle formed integral with said bed, said receptacle extending upwardly toward and partially housing said carriage so 45 as to provide means for guiding chips away from said carriage and to present a support for said carriage, means for imparting rotation to said spindle, and a compartment for receiving said rotation imparting means so as to position the same separate from said chip receiving receptacle, whereby to maintain said compartment free from chips and the like, the unitary construction of the bed, chip receiving receptacle and spindle supporting section lending increased rigidity to 50 the entire machine structure.

2. In material working apparatus of the class described, a unitary bed including a base formed integral therewith and adapted to rest upon the floor and having a spindle supporting section extending upwardly therefrom and formed integral therewith, a spindle rotatably mounted in said support, a plurality of tool carriages shiftable supported by said unitary bed and adapted to support tools in position to act upon work carried by the spindle, means for effecting movement of said carriages, a chip receiving receptacle formed integral with said bed, said receptacle extending upwardly toward and partially housing said carriage so as to provide means for receiving 55 and guiding chips away from said carriage and

to provide a support for said carriage, a prime mover mounted within said unitary bed for imparting rotation to said spindle, and a compartment for receiving said prime mover so as to position the same separate from said chip receiving receptacle, whereby to maintain said compartment free from chips and the like, the integral arrangement of the unitary bed, base, and spindle support lending increased rigidity to the entire machine structure during the cutting action of the tools supported by said carriage. 10

3. A lathe or machine of like nature including an integral bed having an integral chip and fluid receiving trough extending laterally thereof and having a spindle support formed integral therewith and extending upwardly therefrom, the inner portion of said bed being cored to materially reduce the aggregate weight thereof, a spindle rotatably mounted in said support, a tool 15 carriage shiftable mounted upon said bed, and a prime mover mounted within said bed for imparting rotation to said spindle, and a compartment for receiving said prime mover so as to position the same separate from said chip receiving receptacle, whereby to maintain said compartment free from chips and the like, the integral arrangement of the bed, trough, and spindle support being such as to materially enhance 20 the rigidity of the machine structure. 25

4. A lathe or machine of like nature including an integral bed having an integral chip and fluid receiving trough extending laterally thereof and having a spindle support formed integral therewith and extending upwardly therefrom and an integral partition traversing said bed to direct chips, fluid, and the like to said trough, the inner portion of said bed being cored to materially reduce the aggregate weight thereof, a spindle rotatably mounted in said support, a tool 30 carriage shiftable mounted upon said bed, a prime mover mounted within said bed for imparting rotation to said spindle, and a compartment for receiving said prime mover so as to position the same separate from said chip receiving receptacle, whereby to maintain said compartment free from chips and the like, the integral arrangement of the bed, trough, and spindle support being such as to materially enhance 35 the rigidity of the machine structure. 40

5. In material working apparatus of the class described, a bed, a rotary work supporting spindle mounted thereon, said spindle having a center for carrying a work piece, an oppositely disposed center for supporting one extremity of said work piece, means for imparting rotation to said spindle, a shiftable carriage having a tool for making a peripheral cut on a work piece supported by said spindle, a second carriage for supporting a tool to make a facing cut on said work piece, and a third carriage for supporting a tool to make a grooving cut in the peripheral surface of said work piece, and power feeding means for actuating said carriages in a manner to cause the peripheral cutting tool to completely machine the groove cut portion of the work piece before said grooving tools engage for cutting action, said power feeding means maintaining a uniform feeding rate during the cutting operation and permitting said peripheral and grooving cuts to be completed simultaneously. 55

6. In material working apparatus of the class described, a bed, a rotary work supporting spindle mounted thereon, means for imparting rotation to said spindle, a shiftable carriage having 60

a tool for making a peripheral cut on a work piece supported by said spindle, a second carriage for supporting a tool to make a facing cut on said work piece, and a third carriage for supporting a tool to make a grooving cut in the peripheral surface of said work piece, and power feeding means for actuating said carriages in a manner to cause the peripheral cutting tool to completely machine the groove cut portion of the work piece before said grooving tools engage for cutting action, said power feeding means maintaining a uniform feeding rate during the cutting operation and permitting said peripheral and grooving cuts to be completed simultaneously.

7. In material working apparatus of the class described, a bed, a rotary work supporting spindle mounted thereon, means for imparting rotation to said spindle, a shiftable carriage having a tool for making a peripheral cut on a work piece supported by said spindle, a second carriage for supporting a tool to make a facing cut on said work piece, and a third carriage for supporting a tool to make a grooving cut in the peripheral surface of said work piece, power means for effecting the actuation of the first and second mentioned carriages, and power means associated with one of said carriages for controlling the actuation of the third carriage, whereby a peripheral cut will occur at the grooving position prior to the grooving operation, the peripheral cutting tool serving to completely machine the groove cut portion of the work piece before said grooving tools engage for cutting action, said power means cooperating to maintain a uniform feeding rate during the cutting operation and permitting said peripheral cut and grooving cut to be completed simultaneously.

8. In material working apparatus of the class described, a bed, a rotary work supporting spindle mounted thereon, means for imparting rotation to said spindle, a shiftable carriage having a tool for making a peripheral cut on a work piece supported by said spindle, a second carriage for supporting a tool to make a facing cut on said work piece, and a third oscillatory carriage for supporting a tool to make a grooving cut in the peripheral surface of said work piece, and power feeding means for controlling the actuation of said carriages so that the tool supported by the grooving tool carriage will not engage the work piece until the facing tool has completed a portion of its facing cut past the portion of the work piece to be grooved, said power feeding means maintaining a uniform feeding rate during the cutting operation and permitting said peripheral and grooving cuts to be completed simultaneously.

9. In material working apparatus of the class described, a bed, a rotary work supporting spindle mounted thereon, means for imparting rotation to said spindle, a shiftable carriage having a tool for making a peripheral cut on a work piece supported by said spindle, a second carriage for supporting a tool to make a facing cut on said work piece, and a third carriage for supporting a tool to make a grooving cut in the peripheral surface of said work piece, power feeding means for effecting the actuation of the first and second mentioned carriages, and a cam mechanism associated with one of said carriages for controlling the actuation of the third carriage, whereby a peripheral cut will occur at the grooving position prior to the grooving operation, said power feeding means and cam mechanism coop-

erating to maintain a uniform feeding rate during the cutting operation and permitting said peripheral cut and grooving cut to be completed simultaneously.

10. In material working apparatus of the class described, a machine bed, a rotary work supporting spindle, tool carriages disposed on opposite sides of the spindle axis, one of said carriages being shiftable longitudinally of the spindle axis for effecting a peripheral cut and the other carriage being shiftable transversely of the spindle axis for effecting a facing cut, a hydraulic actuator coupled with each of said carriages for effecting the movement thereof, a third tool carriage for effecting a grooving cut in the work piece, and power feeding means for effecting uniform feeding rate of movement of said third carriage after movement has been imparted to the other carriages, whereby to reduce the stress experienced by the work piece during the cutting operations.

11. The method of performing a turning operation upon a rotary work piece which consists in rotating the work piece, moving a tool inwardly across the face of the work piece to remove stock, moving a second tool longitudinally of the work piece to make a peripheral cut and, when the tool making the facing cut has completed a portion of its facing cut, causing a grooving tool to act upon the periphery of the work piece at a uniform speed which is independent of the facing cut speed, whereby to effect said grooving operation without subjecting the work piece to excessive stresses during the cutting operation.

12. The method of performing a turning operation upon a rotary work piece which consists in rotating the work piece, moving a tool inwardly across the face of the work piece to remove stock, moving a second tool longitudinally of the work piece to make a peripheral cut and, when the tool making the facing cut has completed a portion of its facing cut and the other tool has completed at least a portion of its peripheral cut, causing a grooving tool to act upon the periphery of the work piece at a uniform speed which differs from the speed of the facing cut, whereby to effect said grooving operation without subjecting the work piece to excessive stresses during the cutting operation.

13. The method of performing a turning operation upon a rotary work piece which consists in rotating the work piece, moving a tool inwardly across the face of the work piece to remove stock, moving a second tool longitudinally of the work piece to make a peripheral cut and, when the tool making the facing cut has completed a portion of its facing cut, causing a grooving tool to act upon the periphery of the work piece at a uniform feeding rate, whereby to effect said grooving operation without subjecting the work piece to excessive stresses during the cutting operation, effecting a substantially simultaneous completion of the grooving and facing cuts, and then moving all of said tools out of engagement with the work piece.

14. In material working apparatus of the class described, a frame, a rotary spindle, an oscillatory carriage mounted on said frame, a pivotal guide bar upon which said carriage is adapted to rest, means for effecting the upward movement of the free end of said pivotal guide bar, and means for adjusting the pivotal point of said guide bar.

15. In material working apparatus of the class

- described, a frame, a rotary spindle, an oscillatory carriage mounted on said frame, a pivotal guide bar upon which said carriage is adapted to rest, means for effecting the upward movement of the free end of said pivotal guide bar, an adjustable block forming a pivotal support for said guide bar, and means for adjusting said block to vary the position of the pivoted end of said guide bar.
16. In material working apparatus of the class described, a frame, a rotary spindle, a carriage shiftable in a direction transverse to the spindle axis, hydraulic means for effecting the shifting of said carriage, valve mechanism for controlling the actuation of said hydraulic means, said valve including a cylindrical valve member longitudinally shiftable within a casing, fluid propelling mechanism for delivering fluid to said valve mechanism, a second valve member laterally disposed with respect to the first mentioned valve member and adapted in one shifted position to release fluid from one end of the valve mechanism, whereby to enable the normal fluid pressure to be acting within the opposite end of said valve mechanism to suddenly shift the valve member therein, and control means for mechanically shifting said second valve member in timed relation with respect to the actuation of the carriage.
17. In material working apparatus of the class described, a frame, a rotary spindle, a carriage shiftable in a direction transverse to the spindle axis, hydraulic means for effecting the shifting of said carriage, valve mechanism for controlling the actuation of said hydraulic means, said valve including a cylindrical valve member longitudinally shiftable within a casing, fluid propelling mechanism for delivering fluid to said valve mechanism, a second valve member laterally disposed with respect to the first mentioned valve member and adapted in one shifted position to release fluid from one end of the valve mechanism, whereby to enable the normal fluid pressure to be acting within the opposite end of said valve mechanism to suddenly shift the valve member therein, control means for mechanically shifting said second valve member in timed relation with respect to the actuation of the carriage, and resilient means for normally urging said second valve member in a given direction.
18. In material working apparatus of the class described, a frame, a rotary spindle, a carriage shiftable in a direction transverse to the spindle axis, hydraulic means for effecting the shifting of said carriage, valve mechanism for controlling the actuation of said hydraulic means, said valve including a cylindrical valve member longitudinally shiftable within a casing, fluid propelling mechanism for delivering fluid to said valve mechanism, a second valve member laterally disposed with respect to the first mentioned valve member and adapted in one shifted position to release fluid from one end of the valve mechanism, whereby to enable the normal fluid pressure to be acting within the opposite end of said valve mechanism to suddenly shift the valve member therein, and a control mechanism for mechanically shifting said second valve member in timed relation with respect to the actuation of the carriage.
19. In a hydraulic actuator system for propelling machine parts and the like, a hydraulic actuator including a piston within a cylinder, a low pressure pump for imparting rapid traverse to said actuator, a high pressure pump for

imparting feeding movement to said actuator, and a distributor mechanism continuously connected with the discharge side of said low pressure pump for delivering a portion of the fluid discharged by said low pressure pump to said actuator and the remaining portion to said high pressure pump.

20. In material working apparatus of the class described, a frame, a rotary work supporting spindle mounted on said frame, means for imparting rotation to said spindle, a shiftable carriage for supporting a grooving tool, said carriage being shiftable toward and away from a supported work piece for effecting a grooving cut in the periphery thereof, a second carriage for supporting a tool to make a facing cut on the work piece, said second carriage being shiftable toward and away from the axis of a supported work piece, and means for timely controlling the movements of said carriages, whereby the grooving tool supported by said first carriage will travel at a speed differing from that of the tool supported by the other carriage, and whereby the tool in the first carriage will not start its cutting action until the facing tool has completed at least a portion of its cutting stroke.

21. In material working apparatus of the class described, a frame, a rotary work supporting spindle mounted on said frame, means for imparting rotation to said spindle, a shiftable carriage for supporting a grooving tool, said carriage being shiftable toward and away from a supported work piece for effecting a grooving cut in the periphery thereof, a second carriage for supporting a tool to make a facing cut on the work piece, said second carriage being shiftable toward and away from the axis of a supported work piece, and hydraulic actuator system for timely controlling the movements of said carriages, whereby the grooving tool supported by said first carriage will travel at a speed differing from that of the tool supported by the other carriage, and whereby the tool in the first carriage will not start its cutting action until the facing tool has completed at least a portion of its cutting stroke.

22. In material working apparatus of the class described, a frame, a rotary spindle, an oscillatory carriage mounted on said frame, a pivotal guide bar upon which said carriage is adapted to rest, actuating means for effecting the upward movement of the free end of said pivotal guide bar, and abutment means for limiting the upward movement of the free end of said guide bar, said abutment means being secured as a unit with the structure of said actuating means and carried by said frame, whereby to prevent the force exerted by said actuating means from deflecting said abutment means with respect to said frame.

23. In material working apparatus of the class described, a frame, a rotary spindle, an oscillatory carriage mounted on said frame, a pivotal guide bar upon which said carriage is adapted to rest, actuating means for effecting the upward movement of the free end of said pivotal guide bar, and abutment means including a member extending forwardly of the machine, one extremity of said member mounted within the frame and the other extremity secured as a unit with the actuating means whereby to prevent the force of the pivotal bar moving into engagement with said abutment means from causing said abutment means to flex laterally with respect to the frame.

24. In material working apparatus of the class described, a frame, a rotary spindle, a shiftable tool carriage mounted on said frame, means for imparting rotation to said spindle, a hydraulic actuator system for controlling the shifting of said carriage including a fluid pump and a valve mechanism for controlling fluid delivered by said pump, a fluid reservoir for receiving fluid discharged by the pump, said reservoir including inner and outer fluid containers and having a curved surface positioned at the point where the fluid enters the inner container, whereby to counteract any tendency to agitate the fluid body and thereby prevent the introduction of air within said body, and means for conducting fluid from said reservoir to said fluid pump, said reservoir being formed integral with the machine frame.
25. In a hydraulic actuator system for propelling machine parts and the like, a plurality of fluid motors, a source of fluid supply, valve mechanism for controlling the direction and speed of said fluid motors, a rotary disk structure carrying means operable in response to the rotation of said disk for automatically controlling the shifting of said valve mechanism, a second valve mechanism for controlling the starting of at least one of said fluid motors, actuating means for imparting movement to said rotary disk structure in timed relation with the movement of at least one of said fluid motors, connecting means for connecting and disconnecting said rotary disk structure with respect to said actuating means, and manually operable means for shifting said first valve mechanism independently of said rotary disk structure.
26. In a hydraulic actuator system for propelling machine parts and the like, a hydraulic actuator including a cylinder and piston construction, pumping means for delivering fluid to said actuator, said pumping means including a support having a plurality of reciprocable pistons therein for forcing fluid under pressure to said actuator and a tapered valve construction for controlling the flow of fluid toward and away from said pistons, means for automatically maintaining a predetermined adjusted position of the tapered valve within the pumping mechanism, and valve mechanism for controlling the delivery of fluid from said pump mechanism to said actuator.
27. In material working apparatus of the class described, a frame, a rotary spindle, an oscillatory carriage mounted on said frame, a pivotal guide bar upon which said carriage is adapted to rest, means for supporting the pivotal end of the guide bar in various positions, actuating means for effecting the upward movement of the free end of said pivotal guide bar, and abutment means for limiting the upward movement of the free end of said guide bar, said abutment means being secured as a unit with the structure of said actuating means and carried by said frame, whereby to prevent the force exerted by said actuating means from deflecting said abutment means with respect to said frame.
28. In material working apparatus of the class described, a frame, a rotary spindle, an oscillatory carriage mounted on said frame, a pivotal guide bar upon which said carriage is adapted to rest, means for supporting the pivotal end of the guide bar in various positions, actuating means for effecting the upward movement of the free end of said pivotal guide bar, and abutment means including a member extending forwardly of the machine, one extremity of said member mounted within the frame and the other extremity secured as a unit with the actuating means whereby to prevent the force of the pivotal bar moving into engagement with said abutment means from causing said abutment means to flex laterally with respect to the frame.
29. In material working apparatus, a bed, a headstock carried by said bed, a spindle supported in said headstock, a shiftable supporting member, a hydraulic actuator for imparting movement to said supporting member, fluid pressure generating means hydraulically coupled with said actuator, and a fluid reservoir formed integral with said headstock, and means hydraulically connecting said reservoir with said fluid pressure generating means.
30. In material working apparatus, a bed, a headstock carried by said bed, a spindle supported in said headstock, a shiftable supporting member, a hydraulic actuator for imparting movement to said supporting member, fluid pressure generating means hydraulically coupled with said actuator, a fluid reservoir structure forming a unit with said headstock, said reservoir structure including one reservoir mounted within another, and means hydraulically connecting said reservoir with said fluid pressure generating means.
31. In material working apparatus, a machine frame, a spindle rotatably supported by said frame, a supporting means, hydraulic actuator means for imparting relative movement between the supporting means and said spindle, fluid pressure generating means hydraulically coupled with said actuator means, a reservoir structure forming an integral part of said frame structure and including one reservoir within another reservoir, and means hydraulically connecting said reservoir structure with said actuator.
32. In material working apparatus, a bed, a headstock carried by said bed, a spindle supported in said headstock, a shiftable carriage, a hydraulic actuator for imparting movement to said carriage, fluid pressure generating means hydraulically coupled with said actuator, a fluid reservoir structure forming a unit with said headstock, said reservoir structure including one reservoir mounted within another, means hydraulically connecting said reservoir with said fluid pressure generating means, and a restricted fluid conducting means for directing fluid returned to the actuator structure into the inner reservoir.
33. In material working apparatus of the class described, a unitary bed including a base formed integral therewith and adapted to rest upon the floor and having a spindle supporting section formed integral therewith and extending upwardly therefrom, a rotary spindle in said section, a shiftable carriage mounted upon said unitary bed, a motor compartment formed integral with said bed, and means for imparting rotation to said spindle, the unitary construction of the bed and spindle supporting section lending increased rigidity to the entire machine structure.
34. A control mechanism for automatically operated machine tools and the like including a rotary member, a plurality of abutments carried thereby and disposed in a predetermined circumferentially spaced relation in accordance with a desired cycle of operation, a support for said rotary member, a control member shiftable in response to the movement of at least one of said abutments, and means for detachably connecting said rotary member, abutments carried thereby,

and said control member as a unit with said support.

35. A control mechanism for automatically operated machine tools and the like including a rotary member, a plurality of abutments adjustably carried thereby and disposed in a predetermined circumferentially spaced relation in accordance with a desired cycle of operation, a support for said rotary member, a control member 10 shiftable in response to the movement of at least one of said abutments, and means for detachably connecting said rotary member, abutments carried thereby, and said control member as a unit with said support.

36. A control mechanism for automatically operated machine tools and the like including a rotary member, a plurality of abutments secured to the face of said rotary member, at least some of said abutments projecting radially beyond the 20 outer periphery of said rotary member, said abutments being circumferentially disposed in accordance with a predetermined cycle of operation, a support for said rotary member, a control member shiftable in response to the movement of at least 25 one of said abutments, and means for detachably connecting said rotary member, the abutments

carried thereby, and said control member as a unit with said support.

37. A control mechanism for automatically operated machine tools and the like including a rotary member, said rotary member having a circular way, a plurality of abutments adjustably mounted within said way and adapted to be circumferentially spaced in accordance with a desired cycle of operation, a support for said rotary member, a control member shiftable in response to the movement of at least one of said abutments, and means for detachably connecting said rotary member, said abutments, and said control member as a unit with said support. 5 10

38. Control mechanism for machine tools and the like including supporting means, valve means carried by said supporting means, a rotary member carried by said supporting means, abutments carried by and circumferentially spaced upon said rotary member and designed for co-action with 15 said valve means, and a frame structure, said supporting means, together with the valve means and rotary member carried thereby, being detachably supported as a unit by said frame. 20 25
